UNITED STATES PATENT OFFICE

JOHN A. NYLUND, OF PORTLAND, OREGON

TAPERED FEED ROLLER

Application filed November 20, 1929. Serial No. 408,619.

My invention is for use as feed rollers for the feeding of sheets or strips under substantial pressure through drums as in sanding machines, in veneer plants and in the polishing and treating of all forms of sheet stock as paper, veneers, ply-wood, metal strips and the like.

The invention consists primarily of a frame having drums, or sanding rolls or grinding drums disposed therein and through which the material is fed to be polished, ground, surfaced, or finished.

I have observed that in the passing of strips of material to be surfaced or finished through sanding machines that, where a substantial pressure is applied, in order to increase the grinding capacity of the drums a substantial curvature is placed within the drum or roll. This curvature produces a finished surface that lies in a single plane.

Through the use of my new and improved device the grinding sheet will last longer and will maintain a substantial uniform alignment over a relatively long period. This not only gives the finished product a higher utility, but a much better finish as well.

One of the objects of my new and improved device is to increase the capacity of machines where relatively narrow strips are being fed through the machine.

A further object of my invention consists in providing sanding or grinding or polishing drums to which a greater pressure may be applied. This greatly increases the grinding capacity of the drums and at the same time produces a finished sheet or strip, the surface of which will lie in a single plane.

A further object of my invention consists in providing simple means for increasing the life of the grinding sheet that is placed about the grinding or polishing drums.

With these and incidental objects in view, the invention consists in certain novel features of construction and combination of

parts, the essential elements of which are set forth in the appended claims, and a preferred form of embodiment of which is hereinafter shown with reference to the drawing which accompanies and forms a part of this specification.

In the drawing:

Fig. 1 is a sectional, side view of a grinding machine having the principle of my device embodied therein.

Fig. 2 is a sectional, end view taken on line 5—5 of Fig. 1, looking in the direction indicated, the same being made to illustrate feed rolls that uniformly taper from the center towards the oppositely disposed ends.

Fig. 3 is a side view of tapered feed rolls. The same is for use in feeding a plurality of strips continuously and simultaneously through the machine.

Fig. 4 is a sectional, side view of a single grinding and finishing drum, and illustrating the tendency in drums that have uniform diameter to become of a smaller diameter in the center than at the oppositely disposed ends.

Fig. 5 is a side view, in section, of feed rolls or grinding drums made as having a uniformly tapered cross section and being larger in diameter at the center than at the oppositely disposed ends.

Fig. 6 is a side view, illustrating a tempered roll made to compensate for the bend in the roll when the same is being driven at high speed and where a heavy pressure is applied to the center of the roll.

Like reference characters refer to like parts throughout the several views.

The frames of the machine are illustrated at 1 and 2 and have sets of feed rollers 3 and 4 disposed therein and journaled within the side walls of the frame. Sets of grinding, or polishing, drums are shown at 5 and 6 and are in spaced relationship with the sets of feed rollers.

I have observed that in the use of sanding

and polishing drums and especially in veneer plants, or ply-wood plants where sheet stock is being fed through the machines, that there is a tendency to produce finished material having surfaces that do not lie in a single plane. To correct this tendency I have manufactured machines having polishing or grinding drums and feed rolls that have a greater diameter midway their ends and uniformly tapered therefrom. Grinding drums and feed rolls so made produce better stock; the machines so made will handle the stock at a higher rate of speed and produces a finished product that has a higher merchantable value. The capacity of the machines is also greatly increased.

I preferably form my feed rolls, as illustrated at 7 and 8 in Fig. 3 that have their greatest diameter midway the ends of the same and uniformly taper towards the end from the center. When the rolls are so made a plurality of strips shown here as three in number 9, 10 and 11 may be continuously fed through the rolls and each of the strips may be gripped sufficiently to uniformly feed each of the strips through the rolls. A resilient covering 12 is sometimes placed around the drum 13 and the sheet grinding material, as sand paper 14, is placed about the resilient element 12. Where the material has a greater diameter or a greater thickness at its ends than it has in the center, a compensating result may be obtained with equal facility if the drum be made as illustrated in Fig. 6 wherein its maximum diameter is greater towards the ends of the feed portion of the feed rollers.

It is especially desirable where a relatively wide sheet 15, as illustrated in Fig. 2 is being passed through the rollers 16 and 17 that the rollers 16 and 17 have their maximum diameter at the central portion and uniformly taper at the oppositely disposed ends. Where a relatively high pressure is being developed between the rolls, there is a tendency for the rolls to spring sufficiently so that the sheet 15 being passed through the rolls will be thinner at its edges than it is in the center. It is to correct this tendency that I make the rolls tapered and to create a device that will produce a sheet having uniform thickness from edge to edge and to increase the pressure between the grinding or polishing drums.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, a ta-

pered roll, a compressible cover placed about the roll to produce a true cylindrical drum and a grinding element placed about the cylinder.

2. In a device of the class described, the combination in a grinding drum of a tapered roll, a compressible element disposed about the core of the roll, said compressible element being thicker at its ends than at the center and an abrasive element disposed about the outer surface of the compressible element.

JOHN A. NYLUND.
